TUBE FEEDING MACHINE

Nelson D. Abbey, Toledo, Ohio

Application December 5, 1945, Serial No. 632,892

16 Claims. (Cl. 164—61)

1

This invention relates to feeding machines and particularly to feeding machines adapted to recurrently forwardly displace predetermined increments of material.

It is an object of this invention to produce a new and improved feeding machine which is operable automatically to recurrently feed desired increments of material to other processing machines, and, while there being processed, to return preparatory to the next cycle of operation.

Another object of this invention is to produce a new and improved tube clamping and feeding device having novel features of construction, arrangement and operation, said device being adapted for fully automatic or semi-automatic operation in response to hydraulic controls.

Another object of this invention is to produce a new and improved gaging means for controlling the longitudinal movements of the clamping and feeding elements, said gaging means including positive stops in cooperation with adjustable cams.

Another object of this invention is to produce a tube feeding machine having novel tube clamping means associated with an oscillating table which is adapted for the manual adjustment of the traverse rate and for automatic deceleration of the traverse rate near the ends of the longitudinal strokes, thereby to reduce variations in stroke length resulting from more sudden stops.

Another object of this invention is to produce a tube clamping means having replaceable liners for adapting the unit for use with tubing of different diameters.

Another object is to produce an adjustable hydraulic system including novel features of operation and arrangement which is particularly adapted to operate the feeding machine described in a predetermined sequence of movements.

Other objects and advantages will become evident from the description of the invention, and for purposes of illustration, but not of limitation, an embodiment of the invention is shown on the accompanying drawings in which

Figure 1 is a perspective view of the feeding machine which comprises this invention, the same being shown in association with a tube cutting machine;

Figure 1A is a fragmentary view of one side portion of the machine showing the adjustable gauge means;

Figure 2 is a top plan view of the tube feeding machine shown in Figure 1;

2

Figure 3 is a side elevation of the tube feeding machine shown in Figure 1;

Figure 4 is a sectional view along the line 4—4 of Figure 3 showing the clamping elements in detail;

Figure 5 is a perspective view of a pair of guide liners for use in connection with the clamping jaws;

Figure 6 is a sectional view along the line 6—6 of Figure 2;

Figure 7 is a perspective view of the wedge unit with its associated hydraulic actuating means; and

Figure 8 is a diagrammatic view showing the hydraulic system for the sequence of operations of the tube feeding elements.

This invention relates particularly to feeding machines, the illustrated embodiment of the invention, however, showing a tube feeding machine designed to automatically clamp a length of tubing, move said tubing forward a measured distance, and while said tubing is retained and processed by other means, release said tubing and return to reclamp said tubing preparatory to another feed cycle. Controls are provided whereby the sequence of operations may recur automatically after the initial start by the operator, or else, semi-automatic operation may be secured for instances where changes or adjustments are to be made. Simple adjustments are provided so that the rate of feed can be readily controlled, other adjustments are provided for modifying the clamping jaws for use with tubing of different diameters, and novel means are provided for expeditiously gaging the amount of tubing recurrently fed forward during each cycle.

Feeding machines which comprise this invention are suitable for recurrently feeding measured lengths of material into a machine where it may be further processed, drilled, machined, or severed from the substantially continuous length. For purposes of illustration, I have shown an embodiment of my invention associated with a tube cut-off machine, said latter machine being fully shown and described in my co-pending application Serial No. 608,885 entitled "Tube clamping and severing machine," filed August 4, 1945, now Patent 2,484,601 issued October 11, 1949 and only sufficient description of such machine is given as to enable an understanding of the operation of the feeding machine to be had.

The illustrated embodiment of the invention, referring to Figure 1, shows the tube feeding mechanism F in advance of a cut-off machine C which operates to sever segments of the tubing

T forwardly displaced by the tube clamping device A and its associated elements. Another tube clamping device B operates firmly to grip tubing T and hold it in a stationary position during the period of release of the clamping device A and the severance operation, said clamping device B forming a part of the cut-off machine C which will be referred to in the following description only as it relates to the operation of the feed mechanism of this invention.

The tube feeding machine F consists of a housing 10 within which many of the hydraulic elements, generally designated as H, are disposed and later to be more fully detailed in relation to their function and operation. A pair of spaced guide rails or slideways 11 and 12, extending the length of the housing, are attached by means of bolts 13 to spaced platform members 14 and 15 which are, in turn, rigidly attached to the upper edge portion of said housing. Guide slots 16 and 17 formed between lateral flanges 18 and 19 on said guide rails and the respective platform members 14 and 15 serve to retain horizontally disposed gib plates 20 and 21 bolted to lateral flanges 22 and 23 depending from the edge portions of an integral flat bed table 24 which is reciprocable upon the guide rails 11 and 12 mounted upon the housing 10. It is manifest that the guide rails serve to guide the longitudinal movement of the reciprocable table in relation to the housing, vertical lifting movement being restricted by gibs 20 and 21.

A T-shaped connector 26 disposed between guide rails 11 and 12 and on the under side of the table 24 interconnects the end portion of the table with the forward end of a piston rod 27 (Figure 3) which is connected to a piston (not shown) reciprocable in a cylinder 28. Hydraulic fittings 29 and 30 are provided respectively at the outer and inner ends of the cylinder 28 to admit fluid under pressure to one side or the other of the piston and thereby to move the piston and associated piston rod in one direction or the other. It is apparent that when the piston and its associated piston rod move forwardly or rearwardly, the movement will be related to the flat bed table 24 resulting in table movement in the same direction.

Associated with the top forward portion of the table 24 is a tube clamping device A having jaws 31 and 32 (Figure 4) operating firmly to grip the tubing T and thereby to conduct said tubing forwardly in response to similar movement of the interconnected table and piston. The tube clamping mechanism comprises jaws 31 and 32 which are pivoted intermediate their end portions upon a shaft 33 carried by upright end brackets 34 and 34a (Figure 6) which in turn are bolted to lateral support brackets 35 and 35a, the brackets 34, 34a, 35 and 35a substantially enclosing the lower portion of the tube clamping device. The support brackets 35 and 35a are rigidly secured to the reciprocable table top by means of bolts 36.

Horizontally disposed pins 37 and 38 protrude from the lower ends of each jaw respectively and into a cut away portion 39 (Figure 6) on the under side of the jaws. A coil spring 40 yieldingly interconnects the pins thereby to rock the jaws about their pivot into the open position as illustrated by the broken lines of Figure 4.

A pair of rollers 41 and 42 are mounted on vertical stub shafts 43 depending from the base of jaws 31 and 32 respectively. Interposed between the rollers is a wedge block 44 adapted for

longitudinal movement along the table 24. On the under side of the wedge block is an integral guide strip 45 which slides in an elongate groove 46 disposed along the center portion of the table 24. A notched portion 47 in the upright plate 34 fits the wedge block and holds it against vertical displacement. Forming a part of the wedge block 44 is an upright bracket 48 to which is connected a piston rod 49 having a piston (not shown), reciprocable in a cylinder 50. Fittings 51 and 52 (Figure 2) are adapted to deliver liquid under pressure to opposite ends of the cylinder for driving the piston therein in one direction or the other, thereby to impart corresponding movement to the wedge block.

It is manifest that when pressure fluid is admitted to the cylinder 50 in rear of the piston, the piston rod and wedge block 44 will be moved forwardly, and the rollers 41 and 42 abutting the sides of the wedge block will be cammed laterally. Such lateral movement of the rollers imparts rocking movement concomitantly to the clamping jaws 31 and 32 about their pivotal mounting 33. Thus the jaws are positively moved toward each other to clamping position and at the same time, the coil spring 40 is further tensioned. Movement of the piston rod and wedge block in the opposite direction reduces the span between the rollers 41 and 42 which enables the coil spring 40 to rock the clamping jaws in the opposite direction toward open or unclamped position.

It will be observed that each of the jaws 31 and 32 have arcuate surfaces 53 and 54 to which arcuate liners 55 are secured by screws 56. The liners 55 are intended to be replaceable by others of different sizes to accommodate tubing of different diameters.

For supporting tubing T at the rear end of table 24 is a tapered roller 57. As illustrated in Figure 1, the roller 57 is mounted upon a shaft 58 which is retained at its ends by bearing brackets 59 mounted on spaced upright supports 32. The roller 57 supports the tubing T within the area of the gripping jaws while the latter are in the inoperative position during the rearward movement of clamp A and table 24.

The operations of the machine are controlled by hydraulic means which in turn is regulated by various switch and valve means, as will be hereinafter described. In general it will be understood that the reciprocal movement of table 24 is regulated by an arm-carrying bracket 61 grooved in its upper portion for receipt of a protruding portion of a key nut 161 movable longitudinally in a T-slot 25 recessed in one side of the longitudinal table 24. Apertures in the key nut 161 are screw-threaded for engagement with clamping bolts 162 which project from the bracket 61. It is manifest that tightening the bolts 162 will lock the bracket 61 in the adjusted position.

For obtaining fine adjustments, a horizontally disposed adjustable arm 62 is provided, the arm being screw-threaded for engagement with a threaded aperture extending through the lower portion of the arm-carrying bracket 61. An intersecting slot 61a continues downwardly from the screw-threaded aperture forming bifurcated legs 61b and 61c, leg 61b having a shouldered aperture for receipt of a bolt 161a which engages a registered screw-threaded aperture in leg 61c. Operation of arm 62 in one direction or the other results in lateral adjustment of the arm in relation to the bracket 61. Thereafter, operation of bolt 161a results in convergence of legs 61b and

61c thereby firmly to grasp the arm 62 in the adjusted position.

When the table 24 has reached a predetermined position in its rearward travel, the end of the arm 62 is adapted to abut a positive stop block 63 rigidly mounted upon the base 10, thereby to arrest the rearward movement of the table 24 at a predetermined position. The distance between the free end of the arm 62 and the positive stop block 63 when the table 24 is in its extreme forward position determines the length of movement of the table. It is thus possible to measurably vary the reciprocal movements of the table 24 from a fraction of an inch up to the length of the cylinder 28.

Description of the operations of the feeding machine comprising this invention may be made with reference to the schematic drawing (Figure 8) showing the hydraulic system, the solid lines indicating standard fluid passages and the broken lines designating pilot passages conducting a limited amount of fluid. The feeding mechanisms are hydraulically operated, as previously pointed out, and for this purpose, an electric motor 65 drives a pump 66 which communicates with a fluid reservoir 67. The fluid, such as oil, passes from the pump 66 into an adjustable pressure regulating valve 68 designed to regulate the fluid pressure in the system at a predetermined amount, relieving any excess pressure by allowing liquid to return through a passage 69 to the fluid reservoir 67.

Pressure fluid passes from the pressure regulator 68 to a sequence valve 70 which normally operates as a coupling directing the pressure fluid through the passage 170 and into the valve 71, which valve is juxtaposed between two spaced solenoids 71a and 71b containing longitudinally movable armatures 71c and 71d adapted to laterally displace the valve spool 710 in one direction or the other in response to electrical impulse directed to the respective solenoid by switch members hereinafter described.

Ordinarily, the cycle of operations of the feeding machine commences with the table 24 disposed in the predetermined rearmost position, and the valve spool 710 displaced to the right, thus directing pressure fluid into the communicating passage 73, through fitting 51 and to the cylinder 50, there to rock the clamping jaws 31 and 32 to clamping position, as previously explained.

The clamping operation completed, fluid pressure sequentially builds up through the previously designated passages thereby to unseat a spring valve (not shown) opening the port 70a of the sequence valve 70 which now operates as a T-coupling to direct pressure fluid into the passage 700 and into the valve 72, having aligned spaced solenoids 72a and 72b including armatures 72c and 72d respectively, and a valve spool 720 adapted to direct pressure fluid through one port or the other, for effecting the concomitant movement of the piston and the interconnected table 24 in one direction or the other.

Upon completion of the tube clamping operation, a limit switch (not shown) is tripped thereby to direct electrical current to the solenoid 72b which is energized to effect the lateral displacement of the valve spool 720 to the left, thus admitting pressure fluid into the passage 74, through a spring head valve 75 and the fitting 29, thereby to advance the piston and the interconnected table 24. Obviously the forward table movement is not stopped until the piston

abuts the forward end of the cylinder 28 as previously pointed out. A micro-switch (not shown) located in the forward end of the cylinder 28 is actuated by the piston, thereby to direct electrical current to the solenoid operated valve means (not shown), effecting the operation of the clamping means B associated with the cut-off machine C.

- 10 The rate of the forward movement of the piston and the table 24 may be effectively regulated by the manual adjustment of a metering valve 76 which may by-pass part of the pressure fluid in the passage 74, the by-passed liquid returning through passage 77 to the reservoir 67.
- 15 It is expedient to provide means for substantially reducing the traverse speed of the piston before the end of the cylinder is reached; otherwise the piston and the associated elements will be stopped with considerable impact, which, not infrequently, will alter the adjustments and substantially reduce the life of the machine. For this purpose, the forward end of cylinder 28 is adjustably cushioned, those familiar with the art referring to the cylinder 28 as an "adjustably cushioned head-end cylinder" which is a standard product needing no further description. Suffice it to say that it is effective in substantially reducing the traverse speed of the piston during the final portions of the forward stroke.
- 20 A limit switch (not shown) is operated during the inward movement of the cutting tools (not shown) of the cut off machine C, following in sequence the operation of the clamping device B to clamping position, thereby to direct electrical current to solenoids 72a and 72b effecting the lateral displacement of the valve spool 710 to the left and the valve spool 720 to the right. Passage of pressure fluid through the valve 71 releases the valve spring in the sequence valve 70 which sequentially operates as previously described first to direct pressure fluid into the valve 71 thereby to effect the return of the clamping jaws 31 and 32 to inoperative position, and subsequently to direct pressure fluid into the valve 72 thereby to effect the rearward movement of the piston and table 24.

- 25 As previously pointed out, the return of the table 24 is regulated by the distance between the arm 62 and the positive stop block 63, and since 30 the piston does not dead end upon the rearward end of the cylinder, it is expedient to provide means for substantially reducing the table traverse speed before the arm 62 abuts the stop 63; otherwise the impact of the adjustable arm will 35 necessitate frequent readjustment and replacement. Adequate deceleration means are provided comprising a bracket 79 which is adjustably positioned in the T-slot 25 and is adapted operably to depress a plunger 80a in the valve 80 which is 40 secured to the base 10 at a predetermined distance prior to the contact of the arm 62 with the stop block 63. Normally, pressure fluid from the pressure regulator 68 flows through the passage 81 and the port 62 of the valve 80 and out of the 45 cylinder 28 into passage 83a and then into the spring head valve 75 in which the pressure fluid operates to raise the spring valve thereby to permit the free flow of fluid therethrough which oil is returning from the rearward end of the cylinder 28.

- 50 However, when the plunger 80a is depressed by the bracket 79, pressure fluid no longer flows from the port 83, thus releasing the spring valve in the valve 75, which operates to substantially 55 resist the continued flow therethrough of the

fluid returning from the cylinder 28. Pressure fluid now flows from the port 84 in the valve 80, through the passage 85a and into the check valve 85 which may be manually adjusted to be unseated at a predetermined substantially low pressure, thereby to reduce the fluid pressure in the passages 85a and 81 which operates to reset the pressure regulator 68 to operate at the predetermined low pressure. Manifestly, the reduction of fluid pressure operating on the piston and the resistance to flow of the fluid from out of the rearward end of the cylinder 28, results in the substantial deceleration of the piston movement.

A horizontally disposed arm 790 adjustably secured to the lower portion of the bracket 79 is adapted operably to contact a switch arm 81 operable in a limit switch 86 secured to the base 10, which contact occurs simultaneously with the contact of arm 62 against stop block 63. The limit switch 86 operates to direct electrical current to solenoid 71a which effects the lateral displacement of the valve spool 110 to the right, thereby to permit passage of pressure fluid, which continues to operate at low pressure, to the rearward end of cylinder 50, thereby to reclamp the tubing preparatory to another cycle of operation. Obviously it is advantageous to reclamp the tubing at this time, at reduced pressure for the clamping means B and the cutting tools associated with the cut off machine are still operative, and to reclamp under high pressure would result in the subjection of undue strain upon the tubing T. The pressure regulating valve 68 is not reset to operate at the original high fluid pressure until the solenoid 72a is energized permitting the pressure fluid to flow through the passage 74 and into the check valve 85 there to reseat the spring valve (not shown).

It is evident from the above description that tubing T is firmly gripped at all times by either the clamping means A or the clamping means B and during part of the cycle by both clamping means, thus restricting uncontrolled movement of the tubing T which otherwise would make accurate measurements of consecutive segments of tubing practically impossible.

Manually operated switch buttons (not shown) are also provided for the individual energization of each solenoid 71a, 71b, 72a or 72b thereby to open or close the clamping jaws 31 and 32 for replacement of tubing or the like, or to move the table 24 forwardly or rearwardly for adjustment purposes or the like.

The machine may also be set to operate in automatic sequence in combination with the cut off machine as described above.

The switch and valve means recited in the description comprise standard commercial units which are well-known to those skilled in the art and the detailed descriptions thereof are considered unnecessary.

From the above description, it will be manifest that I have produced a simple and compact feeding machine which may be particularly adapted to recurrently measure and forwardly displace segments of substantially continuous tubing for further processing by other means. The above described feeding machine which operates efficiently and accurately makes use of the various control and fluid pressure means described for regulating the rate and gauging the amount of longitudinal or transverse movement of the interconnected elements over a wide yet accurately controlled range.

It is to be understood that numerous changes

in details of construction, arrangement and operation may be effected without departing from the spirit of the invention especially as defined in the appended claims.

5. What I claim is:

1. In a machine of the class described employing a stationary tube severing device, tube clamping means, mechanism for recurrently advancing a predetermined length of tubing to said tube severing device including a carriage mounted for horizontal reciprocable movement toward and away from said tube severing device, a second tube clamping means mounted on said carriage, means for operating said tube clamping means whereby one or the other of said tube clamping means is effective to grip the tube at all times, said second tube clamping means being effective during the advancing movement of said carriage thereby to feed a predetermined length of tubing and ineffective during the carriage return movement to move relative to said tubing, said first tube clamping means being ineffective during the advancing movement of said carriage thereby to enable relative movement of said advancing tubing, and fluid operating means for actuating carriage movement in both directions through fast and then slow movements.

2. In a machine of the class described employing a stationary tube severing device, a stationary tube clamping means associated with said device, mechanism for recurrently advancing a predetermined length of tubing to said tube severing device including a carriage mounted for horizontal advancing and return movements, a second tube clamping means mounted on said carriage, a common hydraulic system for rendering said tube clamping means effective or ineffective and for effecting longitudinal movement of said carriage in one direction or the other, and means for automatically effecting the sequence of operations whereby one or the other of said tube clamping means is in gripping relation with said tubing at all times, said second tube clamping means being effective during advancing movement of said carriage whereby the tubing is correspondingly displaced with the carriage and ineffective during the return movement of said carriage to enable relative movement between said tubing and carriage, said first tube clamping means being ineffective during forward movement of said carriage and effective during the return movement thereof.

3. In a machine of the class described employing a stationary tube severing device, a tube clamping means cooperative with said device, mechanism for recurrently advancing a predetermined length of tubing to said tube severing device including a carriage mounted for horizontal advancing and return movement, a second tube clamping means mounted on said carriage, linear motor means for effecting movement of said carriage, other linear motor means for rendering said clamping means effective or ineffective, a common hydraulic system for operating said linear motors, means for automatically controlling the sequence of operations of said linear motors including means whereby one or the other of said clamping means is in gripping relation with said tubing at all times, said second clamping means being effective during the advancing movement of said carriage and ineffective during return movement, said first tube clamping means being ineffective during the advancing movement of said carriage, and other means for manually controlling the operations of said linear motors.

4. In a machine of the class described employing a stationary tube severing device, tube clamping means cooperative with said device, mechanism for recurrently advancing a predetermined length of tubing to said tube severing device including a carriage mounted for horizontal advancing and return movement, a second tube clamping means mounted on said carriage, linear motor means for effecting movement of said carriage in both directions, other linear motor means for rendering said clamping means effective or ineffective, a common hydraulic system for operating said linear motors, means for automatically controlling the sequence of operations of said linear motors including means whereby one or the other of said clamping means is in gripping relation with said tubing at all times, said second clamping means being effective during the advancing movement of said carriage and ineffective during return movement, said first tube clamping means being ineffective during the advancing movement of said carriage, and switch means for rendering said first tube clamping means and said tube severing device effective when the carriage has reached the end of its forward stroke:

5. In a machine of the class described employing a stationary tube severing device, a tube clamping means cooperative with said device, mechanism for recurrently advancing a predetermined length of tubing to said tube severing device including a carriage mounted for horizontal advancing and return movement, a second tube clamping means mounted on said carriage, linear motor means for effecting movement of said carriage in both directions, other linear motor means for rendering said clamping means effective or ineffective, a common hydraulic system for operating said linear motors, switch means for automatically initiating the sequence of operations of said linear motors including means whereby said second clamping means is rendered effective during the advancing movement of said carriage and ineffective during its return movement, means whereby said first clamping means and said tube severing device is rendered operative when the carriage has reached the end of its forward stroke, said first clamping means being rendered effective before said second clamping means becomes ineffective thereby to maintain the tubing in gripping relation at all times, and adjustable means for predetermining the return stroke of said carriage for increasing or decreasing the length of tubing delivered to the tube severing device.

6. A machine as claimed in claim 5 in which a stationary base supports the reciprocal carriage, and the means for arresting the rearward movement of the carriage comprises an abutment on one of said carriage and base members, and an adjustable stop on the other of said carriage and base members and disposed to be engaged by said abutment when the predetermined carriage return movement has taken place.

7. A machine as claimed in claim 6 in which the adjustable stop comprises a housing rigid with the base and having a horizontally disposed threaded aperture therein and a horizontally disposed screw threaded arm adjustably engaging said apertured housing, and means for securing said arm in said housing in the adjusted position.

8. In a machine of the class described employing a stationary tube severing device, a tube clamping means cooperative with said device,

mechanism for recurrently advancing a predetermined length of tubing to said tube severing device including a carriage mounted for horizontal advancing and return movement axially of said tube severing device and a second tube clamping means mounted on said carriage, linear motor means for effecting movement of said carriage in both directions, other linear motor means for rendering said clamping means effective or ineffective, a common hydraulic system for operating said linear motors, means for automatically controlling the sequence of operations of said linear motors including means whereby one or the other of said clamping means is in gripping relation with said tubing at all times, said second clamping means being rendered effective during the advancing movement of said carriage and ineffective during return movement, and said first tube clamping means being rendered ineffective during the advancing movement of said carriage, and means for effecting deceleration of said first linear motor means near the end of its stroke in both directions.

9. A machine as claimed in claim 8 in which the means for effecting deceleration of the linear motor comprises means for cushioning the escape of fluid near the forward end of its stroke, and means for reducing the hydraulic pressure operating on the linear motor near the rearward end of its stroke.

10. A machine as claimed in claim 9 in which the means for reducing the hydraulic pressure near the rearward end of its stroke comprises an adjustable bleed valve in the hydraulic system, and adjustable means for rendering said bleed valve effective near the end of rearward carriage movement.

11. In a machine of the class described, tube clamping means, mechanism for recurrently advancing a predetermined length of tubing including a carriage mounted for horizontal reciprocal movement, a second tube clamping means on said carriage, means for operating said tube clamping means whereby one or the other is effective to grip the tubing at all times, said second tube clamping means being effective during the movement of the carriage in one direction of its reciprocal movement to advance a predetermined length of tubing and ineffective during the return movement of the carriage to enable the carriage to move relative to said tubing, the second tube clamping means comprising a pair of rigid members rotatable about a common pivot intermediate their ends, a support for said pivot, means responsive to the operating means for effecting pivotal movement of said rigid member in a direction to grip the tubing, other means constantly urging pivotal movement of said rigid members in the opposite direction and consequently the release of said tubing when the operating means is rendered ineffective in accordance with the position of the carriage, and means for actuating said carriage in both directions.

12. A machine as claimed in claim 11 in which said operating means is rendered effective when the carriage has fully reached the end of its return stroke and ineffective when the carriage has reached the end of its forward stroke and after the first tube clamping means has been rendered effective.

13. A machine as claimed in claim 11 in which a horizontally reciprocal wedge member is interposed between the lower ends of said rigid members to effect divergence thereof when operated in one direction and to enable convergence when

operated in the opposite direction, means for guiding said wedge in movement including a longitudinally disposed strip on the underside of said wedge in engagement with an aligned slot in the support.

14. A machine as claimed in claim 13 in which rollers are rotatably mounted on the ends of said rigid member for engaging the sides of said wedge.

15. In a machine of the class described employing a stationary tube severing device, a tube clamping means cooperative with said device, mechanism for recurrently advancing a predetermined length of tubing to said tube severing device including a carriage mounted for horizontal advancing and return movement axially of said tube severing device, a second tube clamping means mounted on said carriage, linear motor means for effecting movement of said carriage in both directions, other linear motor means for rendering said clamping means effective or ineffective, a common hydraulic system for operating said linear motors, means for automatically effecting the sequence of operations whereby the second tube clamping means is effective during the forward movement of the carriage and ineffective during return movement thereof and said first tube clamping means is rendered effective when the carriage has reached the end of its forward stroke and during severing operations, and means operating in timed relation with the severing device for imparting a dwell to the carriage at the end of its return stroke until severing operations have been completed.

16. In combination with a tube severing device having a tube gripping means, a reciprocable car-

riage, tube gripping means on the carriage operable in one direction of carriage movement to grip the tubing to enable advancing movement thereof a predetermined distance to the tube severing device and in the retracting direction of carriage movement to release the tubing for enabling the carriage to move relative thereto, means for rendering the tube severing device and its tube gripping means effective at the end of the tube advancing stroke whereby the tubing is stationarily gripped during severing operations and during the movement of said carriage in the retracting direction, and a fluid motor for effecting carriage movement in both directions.
